UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,130,175.

Specification of Letters Patent.

Patented Mar. 2, 1915.

Application filed October 12, 1914. Serial No. 866,241.

To all whom it may concern:

Be it known that I, GEORGE P. KINGSBURY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating matrices are released from magazines by suitably actuated escapement devices in the order in which their characters are to appear in print and then assembled in line, the composed line transferred to the face of a mold, 20 the mold filled with molten metal to form a slug or linotype against the matrices which produce the type characters thereon, and the matrices thereafter returned through distributing mechanism to the magazines from 25 which they started.

More particularly, it relates to the escapement actuating devices, and one of the principal advantages secured is their arrangement in more compact and convenient 30 form, so that they occupy materially less space without decrease in their efficiency. This arrangement as well as other constructional features will be described in the specification and finally pointed out in the 35 claims.

In the accompanying drawings, I have shown my invention only in preferred form and by way of example, and as applied to a linotype machine, but obviously many 40 changes and variations may be made therein, and in its mode of application, which will still be comprised within its spirit. Similarly, it may be adapted to other forms 45 of typographical machines, such as type-setters, typecasters and the like, which handle type or dies, instead of matrices. Generally speaking, I desire it to be understood that I do not limit myself to any specific form or embodiment, except in so far as 50 such limitations are specified in the claims.

In the drawings: Figure 1 is a vertical section through the lower end of the magazines, etc., also illustrating the escapement actuating devices; Fig. 2 shows a single cam

yoke, etc.; Fig. 3 is a section on the line 55 3—3 of Fig. 1; Fig. 4 is a view similar to the upper portion of Fig. 1, but showing the parts in different position; Fig. 5 is a plan on the line 5—5 of Fig. 1; and Fig. 6 is a sectional detail on the line 6—6 of Fig. 4. 60

The matrices X and X¹ are stored in the magazines A and A¹, two such magazines being illustrated by way of example, and are released therefrom by the actuation of the respective escapements B and B¹. They 65 then pass through the throat D, which is formed with the upper and lower passages D¹ and D² corresponding to the magazines A and A¹ respectively, and thence through the raceway or front plate E to the further 70 assembling devices, all in the ordinary manner. The escapements B of the magazine A, and the escapements B¹ of the magazine A¹, are controlled respectively by the vertical slides C and C¹, which in turn rest upon 75 and are operated by underlying reeds which are actuated from the keyboard mechanism, all in the manner well understood in the art.

It will be noted that the slides C are located in a plane parallel to and in front of 80 the plane of the slides C¹, and that the former are controlled by the two series of alternately disposed reeds F and F¹, and the latter by the alternately disposed reeds G and G¹. The reeds F, F¹, G, G¹ are so 85 formed and disposed that their ends are located in four distinct planes, and are controlled by the two ranks of underlying cam yokes H, in such manner that each of the 90 yokes of the first rank supports at its opposite ends a reed F and a reed G, and similarly each of the yokes of the second rank supports a reed F¹ and a reed G¹. The reeds F, F¹ and G, G¹ are provided respectively with springs F² and G², which act to 95 return them to normal position after their elevation and hold them in active relation to the cam yokes.

Each of the yokes H is provided with the customary cam J, adapted to be brought 100 into operative relation to the underlying actuating roll K, and is also so arranged that it may be moved pivotally about either end, as shown for instance in Fig. 2, so that either the reed F¹ or G¹ may be actuated from the single yoke at will, as distinguished from the ordinary construction, wherein only one reed may be actuated from the yoke. To 105

permit this action, each of the yokes H is provided at each end with a depending arm H¹, which serves to guide it in its movement and is also formed with a notch or recess H² to receive its pivot; and each of the yokes is also formed near both ends on its under side with recesses H³ in proximity to the recesses H². At each end of the yokes H and beneath them is located a series of sprung 10 pressed dogs or triggers L formed with projecting studs or pivot pins L¹, which in their normal position engage in the recesses H² in the depending arms H¹; and in operative relation to each of the dogs L is an underlying slide M connected to and controlled by a key N of the keyboard.

The operation of the parts will now be readily understood. In their normal position, as shown at the lower left-hand side of 20 Fig. 1, the yoke H is inactive and in engagement with the pivot pins L¹ of the two dogs L at the ends thereof. When a key N is depressed, the corresponding slide M is raised and the dog L tripped, which removes the 25 pivot pin L¹ from the recess H² and locates it under the corresponding recess H³, thus permitting the end of the yoke to descend about the opposite pin L¹ and bring the cam J into operative engagement to the roll K, 30 whereupon the cam yoke is swung upwardly about the opposite pivot L¹ and elevates the overlying reed (as shown by full lines in Fig. 2), which is subsequently returned by its connected spring. This reciprocation of the 35 reed, acting through the overlying short reed or slide, effects the reciprocation of the corresponding escapement and releases the lowermost matrix, which passes to the assembling devices in the manner previously indicated. 40 If the slide M at the opposite end of the yoke had instead been elevated, the other end of the yoke would have been released and elevated together with its overlying reed, as shown by dotted lines in Fig. 2. It will be 45 seen that in this construction, the dogs L and their pins L¹ serve both as locking means and pivots, in such manner that when either is tripped, the yoke turns about the opposite one. By thus securing the actuation of the 50 two reeds from a single yoke, the number of the latter is reduced by half, which results in a material economy of space without interfering with their effective operation. Further, this construction is particularly applicable in cases where it is desired to employ narrow magazines, in which circumstances, and as illustrated in the drawings, two narrow superposed magazines would be 55 employed in the place of a single broad magazine, the magazines being located above the narrowed keyboard mechanism. It will be obvious that such narrow magazines could be employed to contain either an ordinary font divided between them, or a plurality of small special fonts, such as head 60 65

letters and the like, without alteration in the escapement actuating connections. That is to say, the improved machine is thus adapted to materially different kinds of matrices and composition, as is now frequently 70 necessitated in actual practice.

The throat D is divided into channels by the transverse partitions D⁴, which channels correspond in width and location to the channels of the raceway E formed by the partitions E¹. In order to permit access to the interior parts, as for instance if it be desired to change the magazines, I mount the throat D upon the main frame by a pivotal connection D⁵, and also provide means such 80 as the latch D⁶ to engage and hold it in operative relation to the magazines, as shown in Fig. 1. If for any reason it be desired to shift the throat from its normal position, it is unlatched and turned about its pivot to 85 the position indicated in Fig. 4. The throat is also provided with an external pivoted plate D³, which may be turned outward at will to give access to the interior thereof, as indicated in Fig. 4.

As previously stated, the channels of the throat and of the raceway correspond, and this is secured by the registry of the throat partitions D⁴ with the raceway partitions E¹. In order to permit the pivotal movement of the throat D to inoperative position, without disturbing this registry, I preferably form the partitions D⁴ at their ends with slots or recesses D⁷, to receive the ends of the partitions E¹ (see Figs. 4 and 6), so that when the throat is shifted, the partitions may be moved relatively to each other without altering their normal position. Also in order to permit the unimpeded movement of the throat with relation to the front plate, 95 these parts are respectively cut away as at D⁸ and E², so as to avoid interference, as best shown in Fig. 4.

As previously stated, I have shown my invention only in preferred form and by way 100 of example, and as applied to a specific type of mechanism, but obviously many modifications and alterations therein, and in its mode of adaptation, will suggest themselves to those skilled in the art, without departure 105 from its scope.

Having thus described my invention, its construction and mode of operation, what I claim and desire to secure by Letters Patent of the United States, is as follows:

1. In a typographical machine, the combination of a movable cam yoke, and escapement reeds arranged at each end of the yoke, the said yoke being mounted to rock about either of its ends so as to actuate one or the other of the reeds.
2. In a typographical machine, the combination of a movable cam yoke, escapement reeds arranged at each end of the yoke, the said yoke being mounted to rock about either 125 130

of its ends so as to actuate one or the other of the reeds, and means for controlling the action of the cam yoke.

3. In a typographical machine, the combination of a cam yoke, a pair of escapement reeds arranged at the opposite ends of said yoke respectively, and a pair of finger keys for throwing the cam yoke into action, the said yoke being mounted to turn about one or the other of its opposite ends according to the finger key operated.

4. In a typographical machine, the combination of a cam yoke, a sustaining dog arranged at each end of the yoke, and means for tripping one or the other of said dogs, for the purpose described.

5. In a typographical machine, the combination of a cam yoke, a sustaining dog arranged at each end of the yoke, and a pair of finger keys for tripping the said dogs respectively.

6. In a typographical machine, the combination of a cam yoke, a sustaining dog arranged at each end of the yoke, the said yoke being pivotally connected to the dogs, and means for tripping one of said dogs to permit the yoke to rock about the other one.

7. In a typographical machine, the combination of an actuating device, an escapement reed arranged at each end of the device, the said device being mounted to rock so as to actuate one or the other of the reeds.

8. In a typographical machine, the combination of an actuating device, an escapement reed arranged at each end of the device, and means for causing the device to rock about either of its ends to effect the actuation of one or the other of the reeds.

9. In a typographical machine, the combination of a plurality of escapement reeds, a cam yoke in operative relation constantly to all of said reeds, and means for causing the yoke to actuate one or another of the reeds.

10. In a typographical machine, the combination of a plurality of escapement reeds, a corresponding plurality of finger keys, and a single cam yoke in operative relation constantly to all of said reeds and adapted to actuate one or another thereof according to the finger key operated.

In testimony whereof, I have affixed my signature in presence of two witnesses.

GEORGE P. KINGSBURY.
